UNITED STATES PATENT OFFICE.

MORRIS KASSER AND JOSEPH B. KASSER, OF SAN FRANCISCO, CALIFORNIA.

COMPARTMENT-INFLATER FOR SHIPS.

1,156,602.

Specification of Letters Patent. Patented Oct. 12, 1915.

Application filed November 7, 1914. Serial No. 871,425.

To all whom it may concern:

Be it known that we, MORRIS KASSER and JOSEPH B. KASSER, citizens of the United States, residing in the city and county of San Francisco and State of California, have invented a new and useful Improvement in Compartment-Inflaters for Ships, of which the following is a specification.

Our invention relates to compartment inflators for ships and the like wherein a container of compressed air within each compartment operates in conjunction with a collapsible bag therein and with a float valve arranged to inflate the bag when the said compartment is flooded; and the objects of our invention are first, to provide improved means for inflating the compartment of a ship when the same is in danger of being flooded; second, to provide improved means for supplying a container of compressed air to each separate compartment; third, to provide improved means for detaching and renewing a compressed air retainer; fourth, to provide improved means for normally retaining the compressed air within the container; fifth, to provide improved means for automatically retaining the container in connection with the inflating means; sixth, to provide means visible from without the container to indicate the amount of compressed air within the container; and seventh, to provide a separate independent means for inflating each separate compartment.

We accomplish these several features by means of the device disclosed in the drawings forming a part of the present specification wherein like characters of reference are used to designate similar parts throughout the said specification and drawings, and in which—

Figure 1 is a broken horizontal sectional view of a ship disclosing the manner in which the same is provided with separate compartments. Fig. 2 is a broken side elevation of Fig. 1. Fig. 3 is a vertical sectional view of one of the compartments disclosing the inflating mechanism therein in a collapsible condition. Fig. 4 is a view similar to Fig. 3 but disclosing the inflating mechanism in an inflated position. Fig. 5 is a broken sectional front view of the inflating mechanism. Fig. 6 is a vertical sectional view of the valve housing within each compartment disclosing the manner in which the container is detachably secured within the compartment and the manner in which

the check valve therein is retained in an open position. Fig. 7 is a view similar to Fig. 6 but with the container and valve housing shown slightly separated and the check valve closed. Fig. 8 is a broken front elevation of the valve housing disclosing the threaded aperture and the arrangement of the cup shaped valve. Fig. 9 is a rear end elevation of one of the containers disclosing the pressure gage secured thereto.

Referring to the drawings, the numeral 1 is used to designate the outer hull of a ship or vessel and 2 an inner or false hull or wall. The space between the outer wall 1 and the inner wall 2 is separated into compartments by means of the vertical and horizontally disposed walls and floors 3 and 4, respectively.

On the floor 4 of each compartment is rigidly secured a valve housing 5 having a frusto-conical valve seat 6 therein and a threaded aperture 7. Within the seat 6 is rotatably mounted a cup-shaped valve 6'.

The threaded aperture 7 is arranged to engage a threaded extension 8 of a compressed air container 9 having a check valve 10 slidably mounted therein and arranged to be normally held to a valve seat 11 by means of a suitable spring 14 operatively connected to the stem 12 of the said valve 10.

When the extension 8 of the container 9 is secured within the threaded aperture 7 of the valve housing 6, the valve 6' therein will engage the stem 12 of the valve 10 and retain the same in an open position against the tension of the spring 14 as disclosed in Fig. 6 of the drawings.

The valve 6' is provided with a port 18 arranged to register, in one position, with a channel 20 of the hollow extension 22 of the valve housing 5.

Secured to the hollow extension 22 is a collapsible bag 25 arranged to lie in a collapsed state in the bottom of the compartment so that should the said compartment be punctured or injured above the bag, the latter will not thereby be injured.

The cup-shaped valve 6' is provided with a stem 26 to which is rigidly secured a lever 105 27 having a suitable float 28 thereon.

In order to hermetically seal the compartment when the container 9 is secured therein, we have provided an annular flange 30 on the outer end of the said container 9, said annular flange 30 being arranged to press the surface of the inner wall 2 adjacent to

the aperture therein through which the container 9 is inserted. A suitable gasket 31 is provided between the said annular flange 30 and the inner wall 2.

5 The outer end of the container 9 is provided with a recess 16 within which is secured a suitable pressure gage 17 connected to the interior of the said container 9 so that the amount of compressed air within the 10 container may be easily determined without withdrawing the same from the compartment.

The operation is as follows: Should the outer wall 1 of the compartment be punctured and water admitted thereto, the presence of the water will raise the float 28 and cause the port 18 of the valve 6' to register with the channel 20 within the extension 22 to which the collapsible bag 25 is secured or connected. Inasmuch as the check valve 10 is retained in an open position by the valve 6' which engages the stem 14 it is evident that the compressed air will be released from the container 9 and will flow into the 25 bag 25 and thereby cause the said bag to expand and inflate the compartment. The pressure of air within the container is designed to be of sufficient pressure to inflate the bag 25 to such an extent that any water 30 within the compartment will be forced therefrom. Inasmuch as the flange 30 of the container 9 is tightly held against the inner wall 2 by means of the threaded aperture 7 of the housing 5, which engages the threaded extension 8 of the said container 9, it is evident that the water cannot enter the interior of the ship. After the compressed air has been released from a container 9 into a bag 25 the location of the compartment inflated or the location of the damage to the ship, may be readily determined by consulting all of the pressure gages. That gage showing a decrease in pressure will indicate the location of the trouble.

45 It is obvious from the foregoing that we have provided improved means for automatically inflating a punctured compartment of a ship, and also separate independent means for automatically inflating each 50 separate compartment, so that in the case of a sailing ship where there is no available machinery aboard for pumping or compressing air, the compartments may be easily and automatically inflated. Also should one inflating mechanism for one compartment be disabled, it will not affect the other compartments, the containers being easily removable may be easily replaced when exhausted.

60 Having thus described our invention what we claim as new and desire to secure by Letters Patent is—

1. A ship having compartments, each of the compartments being provided with an 65 opening in one wall; a valve casing within

the compartment and alined with the opening; a collapsible bag connected to the valve casing; a valve in the casing to control the passage of gas therethrough to the bag; a float to control the valve to permit such passage when the compartment is flooded; and a compressed air receptacle inserted through the said opening and fixed to the valve casing to supply compressed air to the latter. 70

2. A ship having compartments, each of the compartments being provided with an opening in one wall; a compressed air receptacle inserted through the said opening and having a normally closed check valve therein; a valve casing within the compartment and alined with the opening and adapted to connect with the compressed air receptacle; a collapsible bag connected to the valve casing; a valve in the casing to control the passage of gas therethrough to the bag and adapted to open the check valve within the compressed air receptacle; and a float to control such passage when the compartment is flooded. 75

3. A ship having compartments, each of the compartments being provided with an opening in one wall; a compressed air receptacle inserted through said opening and having a normally closed check valve therein; a valve casing within the compartment alined with the opening therein and adapted to connect with the compressed air receptacle; a collapsible bag connected to the valve casing; a cup-shaped valve within the casing to control the passage of gas therethrough and adapted to open the check valve within the compressed air receptacle; and means adapted to control the cup-shaped valve to permit such passage when the compartment is flooded. 80

4. A ship having compartments, each of the compartments being provided with an opening in one wall; a compressed air receptacle inserted through said opening and having a normally closed check valve therein; a valve casing within the compartment and alined with the opening and adapted to connect with the compressed air receptacle and to retain the said receptacle within the compartment; a collapsible bag connected to the valve casing; a cup-shaped valve within the casing to control the passage of gas therethrough and adapted to open the check valve within the compressed air receptacle; and a float operatively connected to the cup-shaped valve and adapted to control the valve to permit such passage when the compartment is flooded. 100

5. A ship having compartments, each compartment being provided with an opening in one wall; a compressed air receptacle inserted through the opening and having an externally threaded extension on the inner end and an annular flange on the outer end thereof; a valve casing within the compartment 110

ment and alined with the opening, said valve casing being provided with a threaded aperture adapted to connect with the threaded extension of the compressed air receptacle 5 and to thereby retain the same within the compartment and the annular flange thereof against the outer wall of the said compartment; a collapsible bag connected to the valve casing; a cup-shaped valve in the casing to control the passage of gas therethrough and adapted to open the check valve within the compressed air receptacle;

and a float to control the valve to permit such passage when the compartment is flooded.

In witness whereof we have hereunto set our signatures in the presence of two subscribing witnesses.
